(57) **CLAIM**

The ornamental design for encoder/decoder of remote controller for water irrigation, as shown and described.

DESCRIPTION

FIG. 1 is a perspective view of an encoder/decoder in accordance with the present invention;

FIG. 2 is another perspective view, from an opposite position, of the encoder/decoder of FIG. 1;

FIG. 3 is a first end view of the encoder/decoder of FIGS. 1 and 2;

FIG. 4 is an opposite end view of the encoder/decoder of FIGS. 1-3;

FIG. 5 is a first side view of the encoder/decoder of FIGS. 1-4;

FIG. 6 is top view of the encoder/decoder of FIGS. 1-5;

FIG. 7 is another side view of the encoder/decoder of FIGS. 1-6;

FIG. 8 is bottom view of the encoder/decoder of FIGS. 1-7;

FIG. 9 is a perspective view of an outer housing of an encoder/decoder in accordance with the present invention;

FIG. 10 is another perspective view, from an opposite position, of the outer housing of the encoder/decoder of FIG. 9;

FIG. 11 is a first end view of the outer housing of the encoder/decoder of FIGS. 9 and 10;

FIG. 12 is an opposite end view of the outer housing of the encoder/decoder of FIGS. 9-11;

FIG. 13 is a top view of the outer housing of the encoder/decoder of FIGS. 9-12;

FIG. 14 is first side view of the outer housing of the encoder/decoder of FIGS. 9-13;

FIG. 15 is bottom view of the outer housing of the encoder/decoder of FIGS. 9-14; and,

FIG. 16 is another side view of the outer housing of the encoder/decoder of FIGS. 9.

The broken lines shown in the drawing depict portions of the encoder/decoder that form no part of the claimed design.
